(57) **CLAIM**

The ornamental design for a [backlit] mirror [with TV], as shown [and described].

DESCRIPTION

FIG. 1 is a perspective view of a [backlit] mirror [with TV], showing our new design [E];

FIG. 2 is a front view and back view view thereof;

FIG. 3 is a left side view and right side view thereof;

FIG. 4 is a top view and a bottom view thereof;

FIG. 5 is a perspective view of a second embodiment of a [backlit] mirror [with TV] showing our new design;

FIG. 6 is a front view thereof;

FIG. 7 is a left side view and a right side view thereof;

FIG. 8 is a top view and a bottom view thereof; and,

FIG. 9 is a back view thereof.

1 Claim, 5 Drawing Sheets

Matter enclosed in heavy brackets [ ] appears in the original patent, but forms no part of this reissue; matter printed in italics indicates the additions made by reissue.
